UNITED STATES PATENT OFFICE.

JOSEPH HREN, OF KINGSTON, NEW YORK.

Slicing and Wrapping Machine.

1,273,227.

Specification of Letters Patent. Patented July 23, 1918.

Application filed November 23, 1916. Serial No. 132,932.

To all whom it may concern:

Be it known that I, JOSEPH HREN, a citizen of the United States, and a resident of Kingston, in the county of Ulster and State of New York, have invented certain new and useful Improvements in Slicing and Wrapping Machines, of which the following is a specification.

This invention relates to a machine of novel construction for subdividing ice cream or a similar article into slices, and folding wrappers around the bottom, sides and top of such slices.

Briefly stated, the machine comprises a reciprocative slide or carriage which is furnished with a trough shaped depression or container. Webs of paper are stretched over the container, and are cut off to form wrappers which thus bridge the container. The latter is moved beneath a hopper, within the lower end of which are arranged a pair of oppositely movable knives, each of which is provided with a lower substantially horizontal blade, and a plurality of short upright blades that extend at right angles across the horizontal blade. As the ice cream descends in bulk through the hopper, it will drop upon the horizontal blades, while its bottom stratum will be slitted transversely by the upright blades. On next opening the knives, the slitted ice cream will drop upon a slide inserted into the container thus carrying the wrapper with it, while by the next closing movement of the knives, the lower slitted stratum will be cut off from the bulk of the ice cream, thus subdividing said stratum into slabs. The container is next moved away from the hopper and opposite to a pair of folders, between which the charged slide is projected. One of these folders is adapted to turn down one of the flaps of the wrapper, and to simultaneously push the slabs sideways off the slide, and into the second folder which is hollow. This second folder is adapted to turn down the second flap of the wrapper, after which the folder is swung up to place the slabs into an upright position, ready for removal.

The invention comprises more particularly, the peculiar means for cutting the bulk of material into slabs, the peculiar means for folding the wrapper around the slabs, and the various other features of novelty more particularly referred to in the specification and appended claims.

In the accompanying drawings:

Figure 1, is a plan of a slicing and wrapping machine embodying my invention;

Fig. 2, a longitudinal section on line 2—2

Fig. 1;

Fig. 3, a cross section on line 3—3 Fig. 1;

Fig. 4, a horizontal section on line 4—4

Fig. 3;

Fig. 5, a section on line 5—5 Fig. 1;

Fig. 6, a section on line 6—6 Fig. 1;

Figs. 7 and 8, are sections corresponding to the lower portion of Fig. 5, and showing the parts in different positions;

Fig. 9, a sectional detail of the deflecting fork;

Fig. 10, a section on line 10—10 Fig. 1;

Figs. 11 and 12 are similar sections showing the parts in different positions.

The machine comprises a frame 1, along which is adapted to reciprocate, a slide or carriage 2, which is operated from a shaft 3 by pinions 4 and racks 5. The carriage is furnished with a transversely extending trough or container 6 adapted to receive the material to be wrapped. The webs or strips 7 of paper for forming the wrappers are drawn from a reel 8 over a table 9 and thence over trough 6 into engagement with a gripper 10 which is mounted on the carriage to the right of the trough. The gripper is made to close upon webs 7 by means of a tappet 11 and a fixed abutment 12. To the left of the trough, the carriage is furnished with a cutter 13 which is adapted to sever from webs 7 such lengths of paper as are required for forming the individual wrappers.

A slideable platen 14 having arms 15 pivoted at 16, closes up a gap which is formed between table 9 and carriage 2, said platen being operated from the carriage by means of rods 17.

All of the above parts, which are more fully described in Patent No. 1171439 issued to me February 15, 1916, do not form part of the present invention.

The ice cream or other article to be sliced is adapted to be dropped into trough 6 through a hopper which is of the following construction:

From frame 1 rise two posts 18, to which are secured by means of bolts 19 spacing blocks 20 and end plates hereinafter referred to, a pair of parallel windowed side plates 21 that constitute the parallel walls of the hopper. From the top of one of the plates 21

there extends upwardly, a fixed upright guard 22, while there is hinged to the top of the other side plate 21, at 23, a shelf 24, upon which the ice cream to be operated upon is 5 deposited. Shelf 24 is provided with a foot or rest 25 which is automatically withdrawn when the shelf is righted, so that the ice cream is free to then drop into the hopper. This foot is made in the form of an angle 10 bar, one flange of which is adapted to be projected beneath the free lower edge of shelf 24, so as to constitute the rest proper. The other flange of foot 25 is attached to arms 26 that are pivoted to shelf 24 at 27. The 15 arms are retracted from the shelf by springs 28, the tension of which may be adjusted by set screws 29. As shelf 24 is swung up, the operative flange of foot 25 will be withdrawn by springs 28 (Fig. 5), while when the shelf 20 is swung down, the angular edge of the foot, will strike fixed abutments 30 so as to advance the foot beyond the upper face of the shelf (Fig. 6), and thus hold back the bulk 25 of ice cream which is deposited upon the latter.

Intermediate the lower ends of side plates 21, and the upper level of carriage 2, there is formed, a clearance for the accommodation of a pair of cutters, which are adapted to 30 divide the ice cream dropped into the hopper into a plurality of horizontal slices and to subdivide such slices into a plurality of short slabs commonly termed "bricks." Each cutter is composed of a head 31, carrying an 35 approximately horizontal or slightly inclined cutting blade 32, and a plurality of spaced upright cutting blades 33, that extend at right angles across blade 32, so as to subdivide the cutter into a number of open compartments. The opposed blades 33 of the 40 two cutter heads, are alined with each other, and are accommodated within upright slits 34 formed in the lower ends of plates 21. Each of the cutter heads 31, is secured to the 45 lower ends of a pair of links 35, the several links being pivoted at 36 to the end plates 37, of the hopper, and accommodated within the clearance formed between said plates and the posts 18. Means are provided for causing 50 the cutters to alternately approach and recede from each other, so as to thereby alternately project them across and withdraw them from the lower end of the hopper. To this effect, there is journaled in frame 1, a 55 shaft 38, which may be manually turned alternately in opposite directions by means of a handle 39 and gear wheels 40. Upon each end of shaft 38, there is mounted a pinion 41, engaging at diametrically opposite 60 site points, a pair of racks 42 pivoted at 43, to the lower ends of links 35. It will be seen that by turning shaft 38, backward and forward, links 35 will be so swung upon their pivots 36 by a mangle movement that the 65 desired opposed simultaneous movement is

imparted to the cutter heads 31. Upon shaft 38, there is furthermore mounted, a cam 44 which is adapted to engage a finger 45 carried by the upper jaw of gripper 10, as soon as trough 6 has arrived underneath the hopper, so as to open the gripper and thus release the paper wrappers which have been severed from webs 7. In order to permit this operation, the upper gripper jaw is mounted on a pair of angle bars 46 pivoted 75 to carriage 2, at 47 and influenced by springs 48, that have a tendency to close the gripper, when finger 45 is released from cam 44.

As thus far described, the operation is as follows:

The ice cream is dumped from shelf 24 into hopper 21, and the cutters are closed or projected across the lower end of the same (Fig. 7). The ice cream will, during its descent be vertically slitted at its bottom 85 stratum by the upright blades 33, and then come to rest on the horizontal blades 32. The cutters are next retracted, so that the ice cream will drop into the trough 6, and become supported by a slide or false bottom 90 49 fitted into the latter. During this drop the ice cream will carry the paper wrappers 50 with it, and fold them over the sides of the slitted bottom stratum (Fig. 8). The cutters are now again advanced to cut off 95 by horizontal blades 32, the lower horizontal stratum which had previously been slitted by blades 33, so that in this way, part of the ice cream dumped into the hopper is divided into bricks of the desired 100 size. Carriage 2 is now moved to the left so as to withdraw the trough from beneath the hopper, and carry it into alinement with a wing or lateral extension 51 of frame 1. In order to arrest the carriage as soon as 105 this alinement has been effected, there is provided, a pivoted stop 52 operable by treadle 53 through rods 54. While the carriage is being retracted, treadle 53 is depressed, so as to swing stop 52 into the path 110 of the carriage and arrest the same at the proper moment.

Wing 51 is provided with a track 55 upon which slide 49 is adapted to be manually pushed, thus carrying the bricks together 115 with the partly folded wrappers out of the trough. At the ingress end of the track, there is provided a forked deflector 56 which extends across the same and has for its object, to engage the free ends of wrapper 50 120 and turn them slightly over the face of the brick 57 (Fig. 9). Fork 56 is suspended from a rock shaft 58 journaled in a bracket 59 and influenced by a spring 60. A tappet 61 of rock shaft 58 is adapted to engage a 125 cam edge 62 projecting upwardly from one of the posts 63 of cutter 13. By the construction described, the fork 56 will normally be swung away from carriage 2, but as soon as trough 6 has arrived opposite 130

track 55, the fork will by cam 62, be so tilted that it will project a distance over the carriage and into close proximity to the end of the trough (Fig. 1) being thus so positioned

5 as to turn the successive wrappers slightly inward, while the slide 49 is being pushed from trough 6 upon the track 55.

Track 55 is flanked by a pair of folders 64, 65 of peculiar construction, and of which 10 folder 64 is slidable, while folder 65 is pivoted. Folder 64 is made in the form of an angle bar being provided at its free end with an upright section or shoulder, and with a horizontal section or blade extending 15 forwardly from the upper end of said shoulder. Folder 64 is adapted to be reciprocated over the entire width of slide 49, so that during its advance movement, the blade will fold one of the flaps of wrapper 50 over the 20 brick, while the shoulder will thereupon come into engagement with the corresponding upright side of the brick and thus push the latter off the slide. For effecting this result, there depends from the sustaining 25 brace 66 of wing 51 a bearing 67 in which is journaled a rock shaft 68 operated by handle 69. Shaft 68 is provided with arms 70, the upper reduced ends of which engage slotted rods 71 to which folder 64 is secured 30 by bent straps 72. Rods 71 move in bearings 73, so that by turning handle 69 alternately in opposite directions, folder 64 will be reciprocated over slides 69 in the manner desired.

35 Folder 65 is pivoted to wing 51 at 74 and is made hollow or in the form of a long box of U-shaped cross section, the two sides of the box being furnished with a plurality of finger slots 75 formed at such distances 40 apart as correspond to the length of the bricks. When folder 65 is in its horizontal position its open side will face charge 57 as well as folder 64. Thus as the bricks are by folder 64 pushed from the position 45 shown in Fig. 10, laterally off slide 49, they will be carried into the hollow of folder 65 (Fig. 11) during which operation the upper side of the latter will constitute a jaw that will turn the second flap of wrappers 50 over the top of the bricks. Next folder 55 is turned up by means of a handle 76, Fig. 12, so that its open end will be on top, and the several bricks properly inwrapped may be withdrawn by the fingers which are 60 introduced into slots 75, thus completing the operation.

The machine constructed as described, 65 possesses various advantages: The cutters will subdivide the ice cream into bricks having sharply defined outlines; the folders operate not only to turn the wrappers over the bricks, but also to present the latter to the operator in such a handy manner that they may be readily removed; finally, the machine works quickly and accurately, and at

no time necessitates manual contact with its charge, so that modern sanitary conditions are fulfilled.

I claim:

1. A machine of the character described, 70 comprising a container, a slide within the container, a track, means for moving the container into alinement with the track, and a pair of folders flanking the track.

2. A machine of the character described, 75 comprising a container, a slide within the container, a track, means for moving the container into alinement with the track, a wrapper deflecting member extending across the ingress end of the track, and a 80 pair of folders flanking said track.

3. A machine of the character described, 85 comprising a track, a slide adapted to be received thereby, a forked spring-controlled deflector extending across the ingress end of the track, and a pair of folders flanking the track.

4. A machine of the character described, 90 comprising a support adapted to sustain a charge, a hollow folder pivotally mounted at one side of said support, and means for projecting said charge into said folder.

5. A machine of the character described, 95 comprising a support adapted to sustain a charge, a hollow folder pivotally mounted at one side of said support, and an angle bar slidably mounted at the other side of said support and adapted to push said charge into said folder.

6. A machine of the character described, 100 comprising a support adapted to sustain a charge, a hollow pivoted folder having an open side that is adapted to receive said charge when said folder is in a horizontal position, and means for turning said folder 105 into an upright position.

7. A machine of the character described, 110 comprising a support adapted to sustain a charge, a hollow pivoted folder having an open side that is adapted to receive said charge when said folder is in a horizontal position, said folder being provided with a plurality of finger slots, and means for turning said folder into an upright position.

8. A machine of the character described, 115 comprising a support adapted to sustain a charge, and a hollow folder pivoted at one side of the support, said folder being provided with a plurality of finger slots and with an open side that is adapted to face 120 said charge.

9. A machine of the character described, 125 comprising a support adapted to sustain a charge, a first slidable folder provided with an upright shoulder adapted to operatively engage the charge and with a folding blade extending from said shoulder, and a second hollow folder pivoted alongside of the support and having an open side adapted to face said charge.

10. A machine of the character described, comprising a container, a slide within the container, a track, means for moving the container into alinement with the track, a combined folder and pusher at one side of the track, and a hollow folder at the other side of the track.
11. A machine of the character described, comprising a container, a slide within the container, a track, means for moving the container into alinement with the track, a combined slideable folder and pusher, at one side of the track, and a slotted hollow folder pivoted at the other side of the track.

JOSEPH HREN.
